ATTORNEY

UNITED STATES PATENT OFFICE.

OSCAR LARSEN, OF WELLS TOWNSHIP, DELTA COUNTY, MICHIGAN.

HORSE.

1,286,663.

Specification of Letters Patent.

Patented Dec. 3, 1918.

Application filed May 4, 1916, Serial No. 95,478. Renewed May 10, 1918. Serial No. 233,800.

To all whom it may concern:

Be it known that I, OSCAR LARSEN, a citizen of the United States, residing at Wells township, in the county of Delta and State 5 of Michigan, have invented certain new and useful Improvements in Horses, of which the following is a specification.

My invention relates to supports and more particularly to a horse for supporting posts.

10 As the primary object, this invention contemplates the provision of a novel supporting means for receiving posts of cedar so that the posts may be readily and conveniently peeled.

15 Another object, of equal importance as first mentioned object, resides in the provision of retaining pins mounted on stationary and adjustable members of the supporting means for preventing the posts 20 from being accidentally misplaced while they are being peeled, as well as the stop pin to facilitate the maintenance of the post in position.

It is also contemplated by this invention 25 to provide means for adjusting the supporting means and to provide means for reinforcing the supporting means.

Other improvements and novel details in the construction and arrangement of parts 30 will be appreciated from the detailed description below, which is to be read in connection with the accompanying drawings and with the claims forming a part of this specification.

35 In the drawings:

Figure 1 is a longitudinal section of my invention.

Fig. 2 is a transverse section taken on the line 2—2 of Fig. 1, in the direction in which 40 the arrow points.

Fig. 3 is a transverse section taken on the line 3—3 of Fig. 1 in the direction in which the arrow points.

Referring more particularly to the drawings I have provided a supporting means including a stationary member 1 which is cylindrical in contour, being supported by legs 2 which are in turn reinforced by sleeves 3. It is desired that the body 1 be 45 formed of wood and in such cases metallic bands 4 are associated therewith for reinforcing purposes. One end of the body is provided with a recess 5 in which is mounted a metallic sleeve 6.

50 Removably connected to and extending longitudinally from the sleeve 6 is a bar 7

provided at uniformly spaced intervals throughout its length with transverse openings 8. A bolt 9 passes through the outer end of the sleeve 6, being also engaged in 60 one of the openings 8 in the bar for removably connecting the bar to the body 1.

Adjustably associated with the bar 7 is an adjustable member of the supporting means which consists of a ball-like body 10 formed 65 preferably of wood and reinforced by metallic bands 11 which extend circumferentially about the body as illustrated to advantage in the drawings. Supporting legs 12 are removably connected to the body, the 70 lower ends being reinforced by sleeves 13. The body 10 is also provided with a transverse bore in which is rigidly connected a metallic sleeve 14. The outer ends of this sleeve project beyond the surface of the 75 body 10 and has one of the ends provided with transverse openings in which is removably engaged a bolt 15. This bolt is also adapted to removably engage one of the 80 openings 8 in the bar 7 for removably and adjustably maintaining the adjustable member in position on the bar 7.

For the purpose of retaining posts of cedar, or the like on the supporting means I have provided preferably pins 16 and arranged them in divergent relation on the upper surfaces of the bodies 1 and 10 of the stationary adjustable members, respectively, of the supporting means. A spike 17 is rigidly mounted on the upper surface of the 90 body 1 and positioned behind the pin 16 while the shank of the spike has a spur 18 thereon which is adapted to engage the end of the post while it is being peeled as is readily apparent to facilitate the maintenance of the post in position.

Although I have shown the preferred embodiment of my invention, I desire it to be understood that I am not to be limited to the exact construction shown and described. 100 However, I desire that great stress be laid upon the arrangement of the supporting means including the relatively adjusted members as well as the means for holding the members in various adjustable positions. Great stress is also laid upon the means for retaining the posts that are being peeled, on the supporting means.

From the above description taken in connection with the accompanying drawing, it 110 can easily be seen that I have provided a device that is simple in construction, contain-

ing but few simple parts that can be cheaply manufactured and assembled and when assembled can be placed upon the market and sold at a minimum cost.

5 It will be understood that the above description and accompanying drawings comprehend only the general embodiment of my invention and that various minor changes in detail of construction, proportion and arrangement of the parts may be 10 made within the scope of the appended claim and without sacrificing any of the advantages of my invention.

Having thus fully described my invention, 15 what I claim as new and desire to secure by Letters Patent, is:

A device of the character described comprising two members, each of the members

including a body, means for reinforcing both of the bodies, supporting legs depending from the body, a sleeve extending from one of the bodies, another sleeve passing through the other of the bodies, a bar associated with the sleeves in the bodies, means for holding the bar in a stationary position on one of the bodies, means for holding the other body in various adjustable positions on the bar, and means on the upper surfaces of the bodies for holding a post thereon.

20 25 30 In testimony whereof I affix my signature in presence of two witnesses.

OSCAR LARSEN.
